UNITED STATES PATENT OFFICE.

EDGAR T. HAUN, OF SAN DIEGO, CALIFORNIA.

CASEMENT-WINDOW OPERATOR.

Application filed June 28, 1926. Serial No. 119,174.

The present invention relates to improvements in window operating devices, and more particularly to devices for the operating of casement windows.

5 The primary object of the invention is to provide a casement window operator whereby the window sash may be operated from the inside of the building without the necessity of raising or removing of a screen supported 10 by the window casing inwardly of the sash.

A further object of the invention is to provide a novel type of casement sash operators which may be operated for swinging of the sash without the necessity of reaching out of 15 the window when desiring to swing the sash to a closed position in the window frame.

A still further object of the invention is to provide a device of this character which is extremely simple and durable in construction, 20 which may be manufactured at a relatively low cost from stock rods of a suitable gauge, and which devices are of such construction as to permit of the sash being locked in a closed, 25 opened, or intermediate position.

Other objects and advantages of the invention will be apparent during the course of the following detailed description, taken in connection with the accompanying drawings forming a part of this specification and in 30 which drawings:

Figure 1 is a transverse section through a casement window construction and showing the improved device applied thereto for operating of the casement sash.

35 Figure 2 is a transverse sectional view similar to Figure 1 but showing the operator in a locked position for retaining the casement sash in a closed position in the window frame.

40 Figure 3 is an enlarged detail sectional view on line 3—3 of Figure 1 and looking in the direction of the arrows.

Figure 4 is an enlarged vertical section on line 4—4 of Figure 2, looking in the direction of the arrows and showing merely the lower 45 portion of the casement window construction.

Figure 5 is an enlarged fragmentary section on line 5—5 of Figure 1, and showing the construction of the window screen at that portion through which the operator extends.

50 Figure 6 is an enlarged fragmentary section on line 6—6 of Figure 2 and illustrating the locking arrangement for the operating device.

Figure 7 is an enlarged fragmentary section on line 7—7 of Figure 2.

Figure 8 is an enlarged fragmentary perspective view of the hinge connection between the operating device and the casement sash.

Referring to the drawings in detail, and wherein similar reference characters designate corresponding parts throughout the several views, A designates a window casement or frame provided with the casement sash B, C a window screen closing the window opening inwardly of the casement sash B; and D the improved casement sash operator for swinging of the sash B to an open or closed position with respect to the frame A.

Referring to the window frame or casing A, and which is of usual construction, the same comprises a sill 10, stiles 11, and the usual stop beads 12 carried by the confronting faces of the stiles 11 intermediate the longitudinal edges of the stiles and which beads form stops for the casement sash B.

The casement sash B for closing of the opening of the frame A, embodies the lower rail 14 and the side rails 15, the sash being of that type which is hung upon one vertical side to one of the stiles 11 as by means of suitable hinges 16 having one wing secured to the stile and its opposite wing secured to one of the side rails 15 of the sash. With this type of casement window construction, and as will be observed in Figure 2, when the sash is moved to a closed position, the same abuts against the stiles 11 for limiting inward swinging of the sash.

The construction of the window as shown, is commonly known in the art as an outward-opening casement window.

The screen C, and which may either be of the sliding or hinge type, in the example shown embodies a bottom rail 17 resting upon the upper surface of the sill 10, and side rails 18 abutting against the inner edges of the stop beads 12. The screen C in casement windows of this type must necessarily be disposed inwardly of the casement sash in order to permit of the sash being swung outwardly to an open position, and as will be observed in Figure 2 when the sash is swung to a closed position, a space the width of the beads 12 is provided between the sash and screen, and in which space the major portions of the operating means D come to rest when the casement sash is swung to a closed position by the operating means.

Referring now to the casement sash operator D, the same embodies an operating lever

20 in the form of a bell crank, providing a throw arm 21 and a relatively short offset operating arm 22. The operating lever 20 is formed from a flat bar of metal of a suitable gauge, and is pivotally mounted at its apex as by means of a suitable pivot pin 23 to the upper surface of the sill 10. This pivot pin or fulcrum 23 may be in the form of a headed screw turned into the sill 10 at a point 5 relatively close to the outer side of the screen C and in the space formed between the sash B and the screen. Formed at the outer end of the throw arm 21, as by means of bending up an edge portion of the arm, is a stop 24. 10 The offset operating arm 22 extends inwardly through an elongated recess 25 provided in the bottom edge of the bottom rail 17 of the screen to a position whereby the same may be readily grasped for swinging of the lever 15 about its fulcrum pin 23 from a position 20 inwardly of the building. The inner end of the arm 22 may be provided with a suitable operating knob 26. A yieldable flap 27 may be secured to the outer side of the bottom rail 17 above the recess 25 and extend downwardly over the recess in a manner for closing of the recess and yet permitting of free movement of the arm 22 along the recess. 25 As will be observed in Figures 4, 5 and 7, the relatively flat operating lever 20 lies flat upon the upper face of the sill 10. Pivotally connected adjacent the outer end of the throw arm 21, and upon the upper side of the arm, as by a suitable pivot pin 28, is a link 30 having a recess 31 provided in one longitudinal edge thereof and into which the stop 24 of the throw arm moves when the arm and link are in substantial alignment as illustrated in Figure 1. The outer end of the link 30 30 is pivotally connected as by means of a suitable L-shaped bracket 35 to the lower rail 14 of the sash B at a point substantially midway between the side rails 15. This L-shaped bracket 35, and as will be observed in Figure 4, is secured to the inner face of the lower rail 14 at a point spaced slightly upward from the lower edge of the rail for allowing the bracket to clear the stop 36 of the sill 10 when the sash is swung to a closed position. 40 Secured at one end to the operating arm 22, and preferably adjacent the knob 26, and as by means of a suitable rivet or the like 39, is an arcuate shaped locking plate 40 extending in an arc concentric to the pivot pin 23. This locking plate or arm 40, adjacent its connection with the operating arm 22, is provided with an upwardly offset portion 41 which overlies the arm 22, and provides a shoulder 42 adapted to engage one 45 edge of the arm for rigidly retaining the locking plate against swinging movement about its securing pin 39. The locking plate 40 is provided with a series of apertures 44 which are adapted to receive a locking pin 45 carried by the sill 10 and projecting up-

wardly from the upper face of the sill in a path of the arcuate movement of the arcuate shaped locking plate. This arcuate shaped perforated locking plate 40 and co-acting locking pin 45 serve as means for adjustably locking the casement sash B in various angular relations with respect to the window frame A, and in the dotted line showing in Figure 1, the centrally disposed aperture of the locking plate is shown engaged by the pin 45 for retaining the sash in a partially opened locked position. The offset provided in the attaching end of the locking plate 40 disposes the major portion of the plate which is provided with the apertures 44, in surface contact upon the upper face of the sill 10 and it can be seen that upon grasping of the knob 26 that the operating arm 22 may be sprung upwardly for withdrawal of the locking plate from the pin 45 when desiring to adjust or operate the sash B. 75

When the sash B is swung to a fully opened position, the arm 21 and link 30 will be locked by means of the stop 24 and recess 31, in a position for retaining the sash in an opened 90 position, and in which position the locking plate 40 need not necessarily engage the locking pin 45. When the sash is in a fully closed position as in Figure 2, the aperture nearest to the operating arm 22 will receive 95 the locking pin 45. When desiring to open the sash from a fully closed position as in Figure 2, the operator first grasps the knob 26 and upon a slight upward pulling disengages the arcuate locking plate 40 from the locking pin 45, and which freeing of the arm 22 will allow the operating lever 20 to be swung about its fulcrum 23 for swinging of the sash B about its hinges 16. 100

The recess 25 provided in the lower edge of the screen C, is of a length to allow the free end of the locking plate 40 to pass beneath the screen when the operator is in a position for retaining the casement sash in a closed position, and as will be observed in Figure 2 110 a very small portion of the operating device extends inwardly past the screen C when the sash is in a closed position. 110

From the foregoing description it will be apparent that an extremely simple yet efficient type of casement sash operators has been provided whereby the sashes of casement windows provided with screens disposed inwardly of the sash, may be readily operated without raising of the screen, and embodying features whereby the sash may be locked in either an open, closed, or intermediate positions. 115

Changes in detail may be made to the specific form of the invention herein shown and described, without departing from the spirit of the invention or the scope of the following claims. 125

I claim:

1. The combination with a casement window embodying a frame comprising stiles and a 130

sill, a sash hingedly connected at one side edge to one of said stiles for swinging outwardly of the window, and a screen carried by the frame and arranged inwardly of the sash, of an operating means for said sash comprising an operating lever embodying a throw arm and an angularly offset operating arm of relatively less length than said throw arm pivotally connected at its elbow to the upper face of said sill between the sash and screen, said operating arm projecting inwardly of the window through a recess provided in the bottom edge of said screen and capable of being sprung upwardly from the face of the sill, a link pivotally connecting the outer end of the throw arm and the sash, a locking pin projecting from the upper face of said sill inwardly of said screen, and a locking plate rigidly carried by the inner end of the operating arm and provided with a series of arcuately arranged apertures arranged to inter-

engage with said locking pin upon swinging of the operating lever.

2. In an operator for casement windows embodying a sill and a horizontally swinging sash, the combination of an operating lever 25 pivotally connected intermediate its ends to the upper side of said sill and embodying a straight throw arm portion having a stop projection provided at one edge thereof at the outer end of the throw arm, a straight link pivotally connecting the outer end of the arm and the sash and having a recess provided in one edge thereof intermediate the 30 ends of the link for receiving the stop of the throw arm when the arm and link are in longitudinal alignment, and an operating knob carried by the inner end of the operating lever for swinging the lever about its pivotal axis. 35
